UNITED STATES PATENT OFFICE.

JOHN A. HAGERSTROM, OF SCRANTON, PENNSYLVANIA, ASSIGNOR TO VICTOR TYPE-WRITER COMPANY, OF SCRANTON, PENNSYLVANIA, A CORPORATION OF NEW YORK.

PAPER-GUIDE.

1,311,687.

Specification of Letters Patent. Patented July 29, 1919.

Application filed September 29, 1917. Serial No. 194,077.

To all whom it may concern:

Be it known that I, JOHN A. HAGERSTROM, a citizen of the United States, residing at Scranton, in the county of Lackawanna and 5 State of Pennsylvania, have invented certain new and useful Improvements in Paper-Guides, of which the following is a specification.

This invention relates to paper feeding 10 means for typewriting machines and has for its primary object to provide an improved construction, combination, and arrangement of parts in devices of this character. One of the objects of this invention is to provide improved side gages for guiding sheets 15 to the platen and improved means for mounting said side gages in connection with a paper table, which is pivotally mounted to render more accessible the tabulating 20 mechanism in the rear of the machine. Other and further objects will appear in the specification and be pointed out in the appended claims, reference being had to the accompanying drawings which show a 25 preferred embodiment.

In the drawings,—

Figure 1 is a front elevation of a typewriter carriage, parts being broken away to show the preferred embodiment of my invention;

Fig. 2 is a top plan view of the same, parts being broken away;

Fig. 3 is a transverse section of the same, parts being broken away and parts shown 35 in elevation;

Fig. 4 is a fragmentary view taken from the rear and below one of the marginal guides;

Fig. 5 is a rear elevation of one end of 40 the paper table mount.

Referring more particularly to the drawing, the typewriter carriage comprises end frames 1, 2, connected by a longitudinal rail or beam 3. A scale bar 4 also connects 45 the end frames 1 and 2. A fixed plate or table 5 extends between the end frames 1 and 2 and is connected thereto by means of flanges 7. The fixed plate or table 5 is provided with a rearwardly presented flange 6 upon which is slidably mounted adjacent 50 either side of the carriage a slide 8 provided with a downwardly deflected lug 9 at each end of said slide and a centrally disposed tongue or finger 10. Said slide 8 is provided with a forwardly presented plate or 55

apron 11 which carries a side marginal guide 12. This guide 12 serves also as a finger grip. In order to retain the slide 8 in any position to which it may be adjusted on the fixed plate or table 5, a leaf spring 60 13 which is secured to tongue or finger 10 and is interposed between said finger and the plate or table 5, is provided with rounded protuberances 14 and 15 which slidably engage in the rounded corner between the 65 flange 6 and the plate or table 5. It will be understood from this description that the marginal flange or guide 12 constitutes a finger hold, by means of which the slide 8 may be adjusted longitudinally of the 70 carriage. Suitable and efficient means for preventing the top edge of a sheet from engaging the lower edge of the plate or apron 11 upon a retrograde movement of said sheet, may be provided by a rounded bulge 75 or bead 16 formed in the fixed plate or table 5. Thus whenever the top edge of a sheet has gone beyond the lower edge of the plate or apron 11 of the slide 8, should a retrograde movement be imparted thereto, said 80 top edge of the sheet would be guided forwardly by means of the protuberant bead 16, so that it would fall forwardly of the lower edge of the plate or apron 11 and thus be prevented from being caught thereon. The spring is provided with lugs 17 which engage the opposite lateral edges of the tongue or finger 10. By an inspection of Fig. 4 of the drawings, it will be seen that the arms of the leaf spring 13 are of 85 unequal length on opposite sides of the finger 10, the longer arm being arranged adjacent the finger grip 12 (see Figs. 2 and 4). A paper table 18 is journaled at opposite ends upon studs 19. In order to provide suitable means for yieldingly holding the paper table in its rearmost position, a spring 20 has one end passed through a lug 21 on said table, the other end of said spring being turned about a pin or screw 22 carried by an upwardly projecting part of the side frame 1 (see Fig. 5).

I claim:

1. In a typewriter, a carriage provided with end frames, a platen journaled in said end frames, a paper table trunnioned in said end frames, a plate extending between said end frames, said plate being provided with a rearwardly presented flange, and a side gage slidably on said plate, said side gage 110

being provided with means extending around said flange and yieldably engaging said plate.

2. In a typewriter, a carriage provided with end frames, a platen journaled in said end frames, a plate extending between said end frames, a paper table trunnioned in said end frames, and a side gage slidable on said plate, said side gage having portions overhanging the upper edge of said plate or rail and carrying means yieldably engaging the rear face of said plate.

3. In a typewriter, a carriage provided with end frames, a plate connecting said end frames, said plate being provided with

a rearwardly presented flange, a slide slidably engaging said plate and flange and having a finger extending behind the rear edge of said flange and toward said plate, a side paper gage projecting from one end of said slide, and a leaf spring mounted on said finger and slidably engaging the corner between said flange and plate, said leaf spring having an arm extending beyond the end of said slide and opposite to said side paper gage.

JOHN A. HAGERSTROM.
